(57) **ABSTRACT**

The present disclosure relates to a dual-band antenna array with fan beam and pencil beam. The antenna comprises a substrate and an antenna array arranged on the surface of the substrate, a first antenna element and a second antenna element are cascaded in an x-axis direction by a filter phase-shift line so as to form a subarray. A pair of T-shaped monopoles are symmetrically placed along the x axis at a certain distance above and below each of the first and second antenna elements, respectively, and a rectangular slot is embedded in the upper edge of the second antenna element to achieve good impedance matching. The second antenna element generates a fan beam at one frequency point or frequency band to have the performance of a wide beam, and generates a pencil beam at another frequency point or frequency band to have the performance of a narrow beam.

DUAL-BAND ANTENNA ARRAY WITH BOTH
FAN BEAM AND PENCIL BEAMCROSS-REFERENCE TO RELATED
APPLICATION

This patent application claims the benefit and priority of Chinese Patent Application No. 202111457639.9, filed with the China National Intellectual Property Administration on Dec. 2, 2021, the disclosure of which is incorporated by reference herein in its entirety as part of the present application.

TECHNICAL FIELD

The present disclosure belongs to the technical field of antennas, and relates to a dual-band antenna array with both fan beam and pencil beam.

BACKGROUND

The antenna has wide-beam characteristics when the radiation pattern is a fan beam, such that the antenna has wider signal coverage area, and is suitable for point-to-multiple communication. The antenna has narrow-beam characteristics when the radiation pattern thereof is pencil beam, and thus the antenna is better able to radiate in a specific direction to make the signal transmission distance farther under the same conditions, and is suitable for point-to-point communication. In a typical outdoor Ethernet bridging system, a directional antenna provides the fan beam and pencil beam simultaneously to satisfy the wide coverage of the signals at the same time, thus being suitable for operating distance requirements for the backhaul during point-to-multiple communication and point-to-point communication. Therefore, it is necessary to develop a dual-frequency antenna with a fan beam at one frequency point or frequency band and a pencil beam at another frequency point or frequency band.

To this end, a dual-band antenna array with both fan beam and pencil beam is provided to solve the problem above.

SUMMARY

To this end, an objective of the present disclosure is to provide a dual-band antenna array with both fan beam and pencil beam. In accordance with the structure, a subarray is composed of a first antenna element and a second antenna element which are cascaded in an x-axis direction by a filter phase-shift line, and then the subarrays are arranged in a y-axis direction to form a 2*4 array, finally achieving the purpose of having both the fan beam and the pencil beam. The developed antenna array is applied to an outdoor wireless Ethernet bridging system to achieve good point-to-point and point-to-multiple communication.

To achieve the objective above, the present disclosure provides the following technical solution:

In accordance with a dual-band antenna array with both fan beam and pencil beam, a distance d between two adjacent antenna subarrays is 49 mm, and the two adjacent antenna subarrays are arranged in the y-axis direction. Each of antenna subarrays is composed of a first antenna element and second antenna element which are cascaded in an x-axis direction by a filter phase-shift line.

Alternatively, the antenna subarray further comprises two pairs of T-shaped monopoles, that is, a first monopole 5 and a first metallic post 13 loaded in the monopole as well as a

2

fifth monopole 9 and a fifth metallic post 17 loaded in the monopole are symmetrically placed at the upper side of a micro-strip patch 21, respectively.

Alternatively, the antenna subarray further comprises two pairs of T-shaped monopoles, that is, a second monopole 6 and a second metallic post 14 loaded in the monopole as well as a sixth monopole 10 and a sixth metallic post 18 loaded in the monopole are symmetrically placed at the lower side of the micro-strip patch 21, respectively.

Alternatively, the antenna subarray further comprises two pairs of T-shaped monopoles, that is, a third monopole 7 and a third metallic post 15 loaded in the monopole as well as a seventh monopole 11 and a seventh metallic post 19 loaded in the monopole are symmetrically placed at the upper side of a micro-strip patch 22 in the second antenna element.

Alternatively, the antenna subarray further comprises two pairs of T-shaped monopoles, that is, a fourth monopole 8 and a fourth metallic post 16 loaded in the monopole as well as an eighth monopole 12 and an eighth metallic post 20

loaded in the monopole are symmetrically placed at the lower side of the micro-strip patch 22 in the second antenna element. A slot 23 etched in the second antenna element is etched on the upper edge of the micro-strip patch 22 in the second antenna element.

Alternatively, the filter phase-shift line 24 is formed by bending and connecting seven stubs.

Alternatively, the substrate 1 is made of F4B (polytetrafluoroethylene), with a dielectric constant of 2.2, a loss tangent of 0.0009, and a thickness of 3 mm.

The present disclosure has the beneficial effects that:

(1) As the radiation pattern characteristics of wide beam can be provided at low frequency band, the dual-band antenna array is wide in wireless signal coverage range and suitable for point-to-multi communication.

(2) As the radiation pattern characteristics of narrow beam can be provided at high frequency band, the dual-band antenna array can transmit the signal towards a certain particular direction farther, and is suitable for point-to-point communication.

(3) As the radiation pattern characteristics of both wide and narrow beams can be provided at the same time, the dual-band antenna array can be applied to point-to-point and point-to-multi communication at the same time, and is very suitable for outdoor wireless Ethernet bridging system.

Other advantages, objectives and features of the present disclosure will be set forth in part in the following description, and to some extent, will be apparent to those skilled in the art based on the study of the following, or can be taught from the practice of the present disclosure. The objectives and other advantages of the present disclosure may be realized and attained through the following specification.

BRIEF DESCRIPTION OF THE DRAWINGS

To make the objectives, technical solutions and advantages of the present disclosure more clearly, the present disclosure will be preferably described in detail below with reference to the accompanying drawings, in which:

FIG. 1 is a three-dimensional view of a dual-band antenna array in accordance with the present disclosure;

FIG. 2 is a front view of a first antenna element of a dual-band antenna subarray in accordance with the present disclosure;

FIG. 3 is a front view of a second antenna element of a dual-band antenna subarray in accordance with the present disclosure;

FIG. 4 is a front view of the dual-band antenna subarray in accordance with the present disclosure;

FIG. 5 is a front view of a filter phase-shift line in accordance with the present disclosure;

FIG. 6 is a curve of S parameters of various ports of the dual-band antenna array in accordance with the present disclosure;

FIG. 7 is a radiation pattern of the dual-band antenna array with a wide beam in accordance with the present disclosure;

FIG. 8 is a radiation pattern of the dual-band antenna array with a narrow beam in accordance with the present disclosure.

In the drawings: 1—substrate; 2—first micro-strip line; 3—second micro-strip line; 4—substrate; 5—first monopole; 6—second monopole; 7—third monopole; 8—fourth monopole; 9—fifth monopole; 10—sixth monopole; 11—seventh monopole; 12—eighth monopole; 13—first metallic post loaded in monopole; 14—second metallic post loaded in monopole; 15—third metallic post loaded in monopole; 16—fourth metallic post loaded in monopole; 17—fifth metallic post loaded in monopole; 18—sixth metallic post loaded in monopole; 19—seventh metallic post loaded in monopole; 20—eighth metallic post loaded in monopole; 21—micro-strip patch in first antenna element; 22—micro-strip patch in second antenna element; 23—slot etched in second antenna element; 24—filter phase-shift line; 25—first stub; 26—second stub; 27—third stub; 28—fourth stub; 29—fifth stub; 30—sixth stub; 31—seventh stub.

DETAILED DESCRIPTION OF THE EMBODIMENTS

The embodiments of the present disclosure are described below by way of specific examples, and additional advantages and efficacy of the present disclosure will be readily apparent to those skilled in the art from the contents disclosed in the present description. The present disclosure may be further implemented or applied through other different specific embodiments, and various modifications or changes may also be made to each of the details in the present description based on different perspectives and applications without departing from the spirit of the present disclosure. It needs to be noted that the drawings provided in the embodiment only explain the basic conception of the present invention in an illustrative manner, and the following embodiments and the features in the embodiments may be combined with each other on a non-conflict basis.

The accompanying drawings are merely exemplarily illustrative, representing schematic diagrams but not physical diagrams, and shall not be regarded as limiting the present disclosure. In order to better describe the embodiments of the present disclosure, some elements in the accompanying drawings may be omitted, enlarged or reduced, and such elements in the accompanying drawings do not represent the real size of products. It should be understood by those skilled in the art that some well-known structures in the accompanying drawings and description thereof may be omitted.

Identical or similar reference numerals in the accompanying drawings in the embodiments of the present disclosure correspond to identical or similar elements. In the description of the present disclosure, it should be understood that the orientation or position relationship indicated by terms such as "up", "down", "left", "right", "vertical" and "horizontal" is an orientation or position relationship shown

based on the accompanying drawings, which is merely used for conveniently describing the present disclosure and simplifying the description, rather than indicating or implying that the device or element must have a particular orientation or must be constructed and operated in a particular orientation. Therefore, the terms for describing the position relationships in the accompanying drawings are merely exemplarily illustrative and shall not be regarded as limiting the present disclosure. For those of ordinary skill in the art, the specific meanings of the above terms may be understood according to specific situations.

FIG. 1 is a three-dimensional view of a dual-band antenna array in accordance with the present disclosure. As shown in FIG. 1, in the embodiment, a distance d between adjacent subarrays in the dual-band antenna array is 46 mm to 52 mm, and a substrate 1 has a length L_{14} of 200 mm to 220 mm and a width W_{14} of 70 mm to 90 mm.

FIG. 2 is a front view of a first antenna element in the dual-band antenna subarray in accordance with the present disclosure. FIG. 3 is a front view of a second antenna element in the dual-band antenna subarray in accordance with the present disclosure. FIG. 4 is a front view of the dual-band antenna subarray in accordance with the present disclosure. FIG. 5 is a front view of a filter phase-shift line in accordance with the present disclosure.

As shown in FIG. 2, a pair of T-shaped monopoles are symmetrically loaded above and below a micro-strip patch 21 in the first antenna element.

Preferably, a first monopole 5 and a first metallic post 13 loaded in the monopole as well as a fifth monopole 9 and a fifth metallic post 17 loaded in the monopole are symmetrically placed above the micro-strip patch 21 in the first antenna element. A second monopole 6 and a second metallic post 14 loaded in the monopole as well as a sixth monopole 10 and a sixth metallic post 18 loaded in the monopole are symmetrically placed below the micro-strip patch 21 in the first antenna element. In the embodiment, the metallic posts have the same radius, where the radius R is 2.4 mm to 2.8 mm. The T-shaped monopoles have the same dimension, where the monopole has a length L_1 of 8.875 mm to 9.275 mm, and a width W_1 of 1.8 mm to 2.2 mm. A distance d_1 from the first monopole 5 and the first metallic post 13 loaded in the monopole as well as the fifth monopole 9 and the fifth metallic post 17 loaded in the monopole to the upper edge of the micro-strip patch 21 in the first antenna element is 4 mm to 6 mm. A distance d_2 from the second monopole 6 and the second metallic post 14 loaded in the monopole as well as the sixth monopole 10 and the sixth metallic post 18 loaded in the monopole to the lower edge of the micro-strip patch 21 in the first antenna element is 4 mm to 6 mm. The micro-strip patch 21 in the first antenna element has a length L_2 of 24 mm to 26 mm and a width W_2 of 13.43 mm to 15.43 mm. A second micro-strip line 3 has a length L_3 of 1.8 mm to 2.2 mm and a width W_3 of 6.8 mm to 7.2 mm.

As shown in FIG. 3, two pairs of T-shaped monopoles are symmetrically loaded above and below a micro-strip patch 22 in the second antenna element. A slot 23 etched in the second antenna element is etched on the upper edge of the micro-strip patch 22 in the second antenna element. In the embodiment, the slot has a length L_6 of 2.2 mm to 2.6 mm and a width W_6 of 2.8 mm to 3.2 mm.

Preferably, a third monopole 7 and a third metallic post 15 loaded in the monopole as well as a seventh monopole 11 and a seventh metallic post 19 loaded in the monopole are symmetrically placed above the micro-strip patch 22 in the second antenna element. A fourth monopole 8 and a fourth

metallic post **16** loaded in the monopole as well as an eighth monopole **12** and an eighth metallic post **20** loaded in the monopole are symmetrically placed below the micro-strip patch **22** in the second antenna element. In the embodiment, all monopole dimensions in the second antenna element are the same as those in the first antenna element. A distance d_3 from the third monopole **7** and the third metallic post **15** loaded in the monopole as well as the seventh monopole **11** and the seventh metallic post **19** loaded in the monopole to the upper edge of the micro-strip patch **22** in the second antenna element is 4 mm to 6 mm. A distance d_4 from the fourth monopole **8** and the fourth metallic post **16** loaded in the monopole as well as the eighth monopole **12** and the eighth metallic post **20** loaded in the monopole to the lower edge of the micro-strip patch **22** in the second antenna element is 4 mm to 6 mm. A distance d_5 from the center of the seventh metallic post **19** loaded in the monopole to the left side edge of the seventh monopole **11** is 2.1 mm to 2.5 mm. The micro-strip patch **22** in the second antenna element has a length L_4 of 24.8 mm to 25.2 mm and a width W_4 of 14.23 mm to 14.63 mm. A third stub **27** has a length L_5 of 1.8 mm to 2.2 mm and a width W_5 of 13.8 mm to 14.2 mm.

As shown in FIG. 4, the first antenna element and the second antenna element are connected by the filter phase-shift line **24** in an electric field plane direction to form a subarray. The substrate has a length L_7 of 63 mm to 67 mm and a width W_7 of 80 mm to 84 mm.

As shown in FIG. 5, the filter phase-shift line **24** comprises a first stub **25** which is arranged perpendicular to the upper edge of the substrate **1**, a second stub **26** which is perpendicular to the first stub **25** and extends rightwards from the lower edge of the first stub **25**, the third stub **27** which is perpendicular to the second stub **26** and extends downwards from the right side edge of the second stub **26**, a fourth stub **28** which is perpendicular to the third stub **27** and extends to the left side from the middle part of the third stub **27**, a seventh stub **31** which is perpendicular to the fourth stub **28** and extends downwards from the left side edge of the fourth stub **28**, a fifth stub **29** which is perpendicular to the seventh stub **31** and extends to the right side from the seventh stub **31**, and a sixth stub **30** which is perpendicular to the seventh stub **31** and extends to the right side from the seventh stub **31**.

Preferably, the fourth stub **28**, the fifth stub **29** and the sixth stub **30** are placed at equal intervals, and the fourth stub **28** has the same dimension as the fifth stub **29**. In the embodiment, the first stub **25** has a length L_8 of 0.6 mm to 1 mm and a width W_8 of 11.85 mm to 12.25 mm. The second stub **26** has a length L_9 of 14.7 mm to 15.1 mm and a width W_9 of 0.6 mm to 1 mm. The third stub **27** has a length L_{10} of 0.6 mm to 1 mm and a width W_{10} of 5 mm to 5.4 mm. The fourth stub **28** has a length L_{11} of 13.9 mm to 14.3 mm and a width W_{11} of 0.6 mm to 1 mm. The fifth stub **29** has a length L_{12} of 11.02 mm to 11.42 mm and a width W_{12} of 0.2 mm to 0.6 mm. A distance d_6 between the lower edge of the fifth stub **29** and the upper edge of the sixth stub **30** is 0.2 mm to 0.6 mm. The seventh stub **31** has a length L_{13} of 0.6 mm to 1 mm and a width W_{13} of 13.05 mm to 13.45 mm.

After completing the above initial design, high-frequency electromagnetic simulation software HFSS is used for simulation analysis, and optimal dimensions of various parameters after simulation optimization are as shown in Table 1, where d represents the distance between two adjacent subarrays; d_1 represents the distance from the fifth monopole **9** in the first antenna element to the upper edge of the micro-strip patch **21** in the first antenna element; d_2 represents the distance from the sixth monopole **10** in the first

antenna element to the lower edge of the micro-strip patch **21** in the first antenna element; d_3 represents the distance from the seventh monopole **11** in the second antenna element to the upper edge of the micro-strip patch **22** in the second antenna element; d_4 represents the distance from the eighth monopole **12** in the second antenna element to the lower edge of the micro-strip patch **22** in the second antenna element; d_5 represents the distance from the centers of the metallic posts in the first and second antenna elements to the left side edge of the monopole; d_6 represents the distance from the fifth stub **29** to the upper edge of the sixth stub **30**; L_1 represents the length of the monopole; L_2 represents the length of the micro-patch in the first antenna element; L_3 represents the length of the micro-strip line in the first antenna element; L_4 represents the length of the micro-strip patch in the second antenna element; L_5 represents the length of the micro-strip line in the second antenna element; L_6 represents the length of the slot in the second antenna element; L_7 represents the length of the substrate in the subarray; L_8 represents the length of the first stub **25**; L_9 represents the length of the second stub **26**; L_{10} represents the length of the third stub **27**; L_{11} represents the length of the fourth stub **28**; L_{12} represents the length of the fifth stub **29**; L_{13} represents the length of the seventh stub **31**; W_1 represents the width of the monopole; W_2 represents the width of the micro-strip patch in the first antenna element; W_3 represents the width of the micro-strip line in the first antenna element; W_4 represents the width of the micro-strip patch in the second antenna element; W_5 represents the width of the micro-strip line in the second antenna element; W_6 represents the width of the slot in the second antenna element; W_7 represents the width of the substrate in the subarray; W_8 represents the width of the first stub **25**; W_9 represents the width of the second stub **26**; W_{10} represents the width of the third stub **27**; W_{11} represents the width of the fourth stub **28**; W_{12} represents the width of the fifth stub **29**; W_{13} represents the width of the seventh stub **31**; and D represents the diameter of the metallic post.

In accordance with above parameters, the reflection coefficient characteristic parameters of the designed dual-band antenna array are simulated and tested using the HFSS, with analysis results as follows:

FIG. 6 illustrates simulation and test curves of the reflection coefficients |S_{mm}| of various ports of the dual-frequency antenna array in accordance with the present disclosure. There is good agreement between the simulation result and the test result, and the test result indicates that the antenna is capable of generating two frequency bands at 5 GHz and 5.8 GHz, respectively.

FIG. 7 illustrates radiation pattern characteristics of the dual-band antenna array at 5 GHz in accordance with the present disclosure. The test result indicates that the antenna has good performance characteristics of wide beam in an electric field plane direction to make signal coverage area wider, and is suitable for point-to-multiple communication.

FIG. 8 illustrates radiation pattern characteristics of the dual-band antenna array at 5.8 GHz in accordance with the present disclosure. The test result indicates that the antenna has good performance characteristics of narrow beam in the electric field plane direction, is high in antenna gain and capable of satisfying operating distance requirements for backhaul during point-to-point communication.

It should be noted that, the above embodiments are only for illustrating the technical solutions of the present disclosure, rather than limiting. Although the present disclosure is described in detail with reference to the embodiments, and it should be understood by those of ordinary skill in the art that any modifications or equivalent replacements made to the technical solutions of the present disclosure without departing from the spirit and scope of the technical schemes of the invention should be covered by the claims of the present disclosure.

What is claimed is:

1. A dual-band antenna array with both fan beam and pencil beam, wherein:
the dual-band antenna array is arranged on the upper surface of a substrate (1);

the dual-band antenna array comprises four subarrays arranged in a y-axis direction, with adjacent subarrays spaced at the same distance; and

each of the subarrays is composed of a first antenna element and a second antenna element which are cascaded in an x-axis direction by a filter phase-shift line (24);

wherein the dual-band antenna array further comprises two pairs of T-shaped monopoles, that is, a first monopole (5) and a first metallic post (13) loaded in the monopole as well as a fifth monopole (9) and a fifth metallic post (17) loaded in the monopole are symmetrically placed at the upper side of a micro-strip patch (21), respectively;

wherein the dual-band antenna array further comprises two pairs of T-shaped monopoles, that is, a second monopole (6) and a second metallic post (14) loaded in the monopole as well as a sixth monopole (10) and a sixth metallic post (18) loaded in the monopole are symmetrically placed at the lower side of a micro-strip patch (21) in the first antenna element, respectively; and

wherein the dual-band antenna array further comprises two pairs of T-shaped monopoles, that is, a third monopole (7) and a third metallic post (15) loaded in the monopole as well as a seventh monopole (11) and a seventh metallic post (19) loaded in the monopole are symmetrically placed at the upper side of a micro-strip patch (22) in the second antenna element.

2. The dual-band antenna array with both fan beam and pencil beam according to claim 1, wherein the dual-band antenna array further comprises two pairs of T-shaped monopoles, that is, a fourth monopole (8) and a fourth metallic post (16) loaded in the monopole as well as an eighth monopole (12) and an eighth metallic post (20) loaded in the monopole are symmetrically placed at the lower side of the micro-strip patch (22) in the second antenna element; and a slot (23) etched in the second antenna element is etched on the upper edge of the micro-strip patch (22) in the second antenna element.

3. The dual-band antenna array with both fan beam and pencil beam according to claim 2, wherein the filter phase-shift line (24) is formed by bending and connecting seven stubs.

4. The dual-band antenna array with both fan beam and pencil beam according to claim 1, wherein the substrate (1) is made of F4B, with a dielectric constant of 2.2, a loss tangent of 0.0009, and a thickness of 3 mm.
